DISPENSING APPARATUS

Norman C. Moore, West Newbury, Mass., assignor
to Western Electric Company, Incorporated,
New York, N. Y., a corporation of New York

Application December 8, 1945, Serial No. 633,893

3 Claims. (Cl. 214—8.5)

1

This invention relates to dispensing apparatus, and more particularly to apparatus for dispensing flat articles such as laminations for cores of electrical units.

The various types of laminations used in the forming of cores for electrical units are usually selected manually and considerable time may be required, not only to count the number of laminations, but to assemble them in proper stacked formation.

An object of this invention is to provide a dispensing apparatus for flat articles, such as laminations, which is highly accurate in removing varied numbers of articles from a supply.

Broadly, the dispensing apparatus includes a table to support a supply of flat articles or laminations, a shelf movably mounted at one end of the table to receive a given number of the articles as determined by the setting of a stop on the shelf, and mechanism operated to hold the remaining articles of the supply against movement while the given number of articles on the shelf are removed therefrom.

More specifically, the shelf is pivotally supported at the exit end of the table toward which the supply of articles or laminations are constantly urged by a bar. A fluid operated gripper, functioning in cooperation with the table, is caused to operate through the opening of a valve to grip the last article of the supply adjacent the given number of articles on the shelf, to hold the supply against movement while the shelf is moved about its pivot to position the articles thereon where they may be readily removed. A handle rotates a shaft to move a rack which is carried by a slide, the latter normally supporting the shelf in its receiving position. During the first partial movement of the handle from its normal position, an arm, carried by the slide, releases the valve to operate the gripping element. Further movement of the handle causes the slide to free the shelf which it normally supports in its upward position so that the shelf may move downwardly, by gravity, about its pivot to position the group of laminations thereon free of the supply.

Other objects and advantages will be apparent from the following detailed description when considered in conjunction with the accompanying drawings, wherein

Fig. 1 is a front elevational view of the dispensing apparatus, a portion thereof being broken away;

Fig. 2 is a fragmentary side elevational view

2

of the apparatus, portions thereof being shown in section;

Fig. 3 is a fragmentary top plan view taken substantially along the line 3—3 of Fig. 2;

Fig. 4 is a fragmentary sectional view taken from one side of the front portion of the apparatus; and

Fig. 5 is a vertical sectional view taken along the line 5—5 of Fig. 3.

Referring now to the drawings, the apparatus includes a hollow frame or base 10 which supports a table formed of two sections 11 and 12 connected at the meeting line 13 as shown in Fig. 3. These table sections have upper surfaces which lie in a common plane and have pairs of spaced guides 14 and 15 mounted thereon. The distance between each pair of guides depends upon the length of the articles which are to be dispensed. In the present instance, the articles 16 are laminations, namely thin metal sheets which are disposed upon the table between the guides so that they will rest upon their lower side edges.

The feeding means for the articles includes a movable element 18 which extends laterally of the table and is supported by guide rods 19, the latter extending through openings 20 (Fig. 5) in the element 18. The inner ends of the guide rods 19 are threadedly disposed in suitable apertures 21 (Fig. 3) in their respective guides 15, while the rearmost ends of the guide rods are supported in a bracket 23. The bracket 23 is fixedly mounted upon the table by screws 24 and has apertures 25 to receive the guide rods 19, the latter having their outer ends reduced as at 26 to receive a wrench so that the guide rods may be removed and replaced by other rods if so desired. The element 18 has cables 28 fixed to the outer ends thereof, the cables extending over their respective pulleys 29 and through apertures 30 in the base 10 and also apertures 31 in a bench 32 upon which the apparatus is mounted. The cables further extend around pulleys 33 and 34 (Fig. 1), after which they are connected to a weight 35 which supplies the force necessary to move the element 18 and cause movement of the supply of articles 16 toward the exit end of the table.

A shelf 38 has legs 39 which extend into cut away portions 40 of the table, that is, the adjacent section 12 thereof where they are mounted upon a pivot or shaft 41. The shaft 41 is mounted in suitable bearings in the table. When the shelf 38 is in its normal position, the upper surface 42 thereof is in the plane of the upper surface of

the table so that the articles may be moved from the table onto the shelf. The portion of the table indicated at 44 between the legs 39 of the shelf extends to a line 45 which is the meeting line of the table and shelf. Vertically extending members 47 of the shelf are apertured to receive screws 48 by the aid of which stops 49 of varied thickness may be mounted on the shelf to vary the number of articles or laminations which are to be moved onto the shelf. If desired, the stops 49 may be of varied numbers, depending upon the space they are to consume between the portions 47 and the last article of the supply on the table. Resilient members or springs 50 mounted upon the shelf 38 extend inwardly toward the table beyond the exit end of the table to hold the articles moved onto the shelf against accidental displacement during the lowering of the shelf to the position shown in Fig. 4.

A gripping element 52 is supported adjacent its ends by springs 53 which are disposed concentric with guide pins 54, the latter being receivable in apertures in the guides 15 and extending through apertures in the ends of the element. The element 52 has a reduced portion 55 which is parallel with the exit edge of the table and cooperates therewith to grip the last article of the supply adjacent the group which has been moved onto the shelf. The reduced portion 55 is normally positioned above the supply of articles and held in that position by the springs 53. The element is moved into its gripping position by a plunger 56 of an air cylinder unit 57. The unit 57 is supported by a bracket 58 and is under the control of a valve 59 (Figs. 2, 3, and 4). A pressure pad 60 carried by screws 61 is positioned to assist the gripping element in holding the articles of the supply by applying pressure to a plurality of the articles back of the reduced portion 55 as illustrated in Fig. 4. The pressure applied to the pad is received from springs 62 partially housed in the element 52. The screws 61 are movable in apertures in the element 52, their heads 64 limiting the downward movement of the pressure pad.

A shaft 70 is journalled in suitable bearings 71 in the base 10 and is rotated by the aid of a handle 72. A pinion 73 is keyed to the shaft 70 and interengages a rack 74. The rack 74 is supported by a slide 76 which is movable in guideways 77 positioned beneath the table section 12 and the shelf 38. The function of the slide 76 is to normally hold the shelf 38 in its upward position and to release the shelf for its movement downward to the position shown in Fig. 4. The slide 76 also supports an arm 78 which carries an adjustable screw 79 positioned to engage a valve plunger 80, the latter being normally urged outwardly to open the valve 59.

Upon considering the operation of the apparatus, let it first be assumed that the table has been filled with a supply of articles or laminations 16 which may be accomplished by moving the element 18 rearwardly (to the left Figs. 2 and 3) by the aid of its handle 81. The apparatus as shown in Figs. 2 and 3 is in its normal position with the shelf 38 in alignment with the table. The weight 35 has caused forward movement of the element 18 to move the entire supply of articles to the right to load the shelf with the given number of articles. The operator may, at this time, move the handle 72 from the solid line position shown in Fig. 2 to the dotted position shown in this figure. During the first portion or approximately one quarter of the movement of

the handle in this direction, the pinion 73 causes movement of the rack 74 to move the slide 76 (Fig. 2) to the left, moving with it the arm 78 to free the valve plunger 80 to open the valve 59. The unit 57 is therefore actuated by the application of a fluid under pressure thereto to move the plunger 56 thereof downwardly and move the element 52 into gripping position. The leading article of the supply adjacent the articles on the shelf has therefore been firmly gripped between the reduced portion 55 and the table. Furthermore, the gripping element has been assisted by the pressure pad 60 in holding the articles remaining in the supply from forward movement.

Continued movement of the handle 72 causes continued movement of the slide 76 to free the shelf 38 so that it may move, by gravity, about its pivot to the position shown in Fig. 4. While in this position, the articles may be readily removed from the shelf in their stacked formation, an accurate number of the articles being in this group due to the measured distance between the stops 49 and the edge of the table.

The apparatus may now be returned to its normal position by moving the handle 72 from the dotted position to the full line position shown in Fig. 2 to first return the shelf 38 to its upward position by the movement of the slide 76 to the right, after which the arm 78, with its screw 79, will move the plunger 80 of the valve inwardly to again close the valve and permit the fluid in the unit to escape by any conventional means (not shown). The element 52, with its pressure pad 60, will be moved upwardly by the force of the springs 53 to free the supply of articles for movement to the right by the continued force of the element 18. The springs 50 hold the leading articles of the supply in their vertical position during their movement onto the shelf. The shelf immediately becomes loaded again with the desired number of laminations and the cycle of operation may be repeated. When the supply is reduced to the point where the element 18 approaches the guides 15, the operator may move the element 18 rearwardly into engagement with the bracket 23 and fill the space between the element and the articles on the table with an added number of articles to replenish the supply. With this mechanism, a predetermined variable number of articles may be dispensed in stacked formation merely by the rocking movement of the handle 72 from its normal to its operating position.

Although specific improvements of the invention have been shown and described, it will be understood that they are but illustrative and that various modifications may be made therein without departing from the scope and spirit of this invention as defined by the appended claims.

What is claimed is:

1. A dispensing apparatus comprising a table having a support surface for a supply of closely positioned flat articles resting edgewise on the table, a shelf, pivotally supported at an exit end of the table and having a supporting surface lying in the plane of the supporting surface of the table when in its loading position, movable to an unloading position, a slide movable beneath the table and the shelf to hold the shelf in its loading position, free the shelf for movement into its unloading position and move the shelf into its loading position, means to move the slide, means urging the supply of articles toward and onto the shelf, a stop on the shelf to limit the number of articles to be loaded on the shelf,

actuable means including an element cooperating with the table to grip the article at the exit end of the table to hold the supply of articles on the table against movement, and a unit operable by the slide when moved in one direction to cause actuation of the last named means prior to the slide releasing the shelf for movement into its unloading position.

2. A dispensing apparatus comprising a table having a support surface for a supply of closely positioned flat articles resting edgewise on the table, a shelf, pivotally supported at an exit end of the table and having a supporting surface lying in the plane of the supporting surface of the table when in its loading position, movable to an unloading position, a slide movable beneath the table and the shelf to hold the shelf in its loading position, free the shelf for movement into its unloading position and move the shelf into its loading position, means to move the slide, means urging the supply of articles toward and onto the shelf, a stop on the shelf to limit the number of articles to be loaded on the shelf, actuable means including an element cooperating with the table to grip the article at the exit end of the table to hold the supply of articles on the table against movement, and a unit operable by the slide when moved in one direction to cause actuation of the last named means prior to the slide releasing the shelf for movement into its unloading position, and also operable by the slide when moved in the opposite direction to cause the actuable means and element to release the leading article of the supply subsequent to the return of the shelf to its loading position by the slide.

3. A dispensing apparatus comprising a table to support a supply of flat articles, a shelf piv-

otally supported at the exit end of the table for movement between a loading position in alignment with the table and an unloading position away from the table, a stop on the shelf to limit the number of articles moved onto the shelf, means to move the supply of articles to feed a given number of the articles to the shelf, a fluid actuated gripping means to cause gripping of the first article of the supply adjacent the given number of articles on the shelf, a fluid control valve actuatable to cause operation of the gripping means, an element movable in one direction to move the shelf into its loading position and movable in another direction to free the shelf for movement into its unloading position, means to move the element alternately in the said directions, and means movable with the element to actuate the valve during predetermined portions of the movements of the element to cause the gripping means to be actuated into gripping position prior to the time the element frees the shelf for movement out of its loading position and to cause the gripping means to be actuated out of gripping position after the shelf returns to the loading position.
